[57] CLAIM

The ornamental design for filter for cleaning fluid or the like, substantially as shown and described.

DESCRIPTION

FIG. 1 is a perspective view of the filter for cleaning fluid or the like showing my new design.

FIG. 2 is a side elevational view thereof, the opposite side being a minor image of the side shown;

FIG. 3 is a front elevational view thereof, a portion of the upper tank being broken away for convenience of illustration;

FIG. 4 is a rear elevational view thereof;

FIG. 5 is a bottom plan view thereof; and

FIG. 6 is a top plan view thereof.

FIG. 1

FIG. 5

FIG. 6

FIG. 3

FIG. 4
